UNITED STATES PATENT OFFICE.

BENJAMIN F. FITCH, OF EVANSTON, ILLINOIS.

FREIGHT-TRANSFERRING MECHANISM.

Application filed July 14, 1920. Serial No. 396,061.

To all whom it may concern:

Be it known that I, BENJAMIN F. FITCH, a citizen of the United States, residing at Evanston, in the county of Cook and State 5 of Illinois, have invented a certain new and useful Improvement in Freight-Transferring Mechanism, of which the following is a full, clear, and exact description, reference being had to the accompanying drawings.

10 My invention relates to hoisting and transporting mechanism primarily adapted for raising and moving the bodies of automobile trucks for use in conjunction with the handling of freight at terminal stations. My invention is specifically adapted for handling loaded truck bodies in a system for handling and transporting freight as set forth in my prior Patent No. 1,275,145, is- 15 sued August 6, 1918.

To facilitate the handling of freight, I provide a raised freight platform between a railway track and a truck runway and employ a hoisting and conveying mechanism of 20 the gantry in the nature of a crane straddling the platform and arranged to travel longitudinally thereof. This crane has the usual supplemental frame, on the main frame, adapted to travel transversely of the 25 station platform track and runway. Thus, I may accomplish lifting and carrying a removable body from a truck, positioned on one side of a freight platform, to a flat railroad car, positioned on the opposite side of 30 the platform, or to any place on the platform.

The principal feature of my invention, is 40 the arrangement of a gantry crane bridging a station platform, between a railroad track and street or runway. Other features including the form and arrangement of 45 cantilever construction of the main frame, the novel construction of the supplemental frame, together with various other characteristics of construction are illustrated, de- 50 scribed and claimed in my co-pending application, Serial No. 554,462, filed April 18, 1922. The essential features of this present case, however, are summarized in the claims.

55 In the drawings Fig. 1 is a side elevation embodying the features of my invention and showing a platform intermediate a truck and a railroad car; Fig. 2 is an end view of the gantry crane taken from the street side 55 of the platform; Fig. 3 is a plan of the

crane with part thereof broken away, to show details of construction; Fig. 4 is a partial layout of a freight platform.

Designating the parts by the use of reference characters in Fig. 1, 1 and 2 represent tracks preferably positioned on the freight platform 3 and on which the wheels 4 are adapted to travel. These wheels 4 are supported in bearing blocks 5 at the foot of the columns 6, which form a support for 60 a gantry crane. The tracks 1 and 2 extend longitudinally of the platform 3 and are spaced apart an amount sufficient to permit several removable truck bodies 7 to be placed on the platform.

70 Referring now to Fig. 2, it will be seen that each bearing block or carriage 5 at the foot of the column carries a pair of wheels, and that there are two pairs of such supporting wheels for each leg of the gantry. Each 75 leg of the gantry is preferably right triangular in form, and comprises a vertical leg 6, a base 17, and a hypotenuse 19. The vertical member 6 may be built up of four angle bars riveted back to back. The base and 80 hypotenuse may comprise two angle bars riveted back to back but spaced apart to provide clearance for suitable reinforcing members or lattice work. This type of construction in each leg of the gantry prevents 85 the crane from tipping when it is brought to a stop. Additional strengthening means is provided between the supporting members which travel on the same track, by connecting bars 18. These bars 18 may be angle 90 plates riveted back to back and connected to the gusset plates at the base of the vertical members 6.

To move the gantry crane longitudinally of the platform, I provide a pinion 8 intermediate the wheels 4 on the vertical member of one leg of the gantry. The pinion 8 is rotated through a set of beveled gears 9 which are driven through the shaft 10 by another set of beveled gears 11 positioned at the top of 100 the vertical member. The upper set of the beveled gears is driven through the worm and wheel 12, and sprocket chain 13, by the motor 14. A shaft 15 on which the worm wheel is secured, extends across the top of 105 the crane and longitudinally thereof, and operates a set of bevel gears 16, to drive the pair of wheels 4 on the track 1.

110 Referring now to Figs. 1 to 3, the main frame of the crane comprises a fabricated

rectangular frame, having the longitudinal members 20 and 21 and transverse members 22 and 23. The longitudinal members are preferably angle bars positioned back to back, while the transverse members are preferably channels which are riveted to the ends of the longitudinal beams. The longitudinal members 20 and 21 are positioned at the top of the columns 6 and rigidly secured thereto.

To prevent deflection of the longitudinal beams 20 and 21, I provide a truss having the upper chords 24-25, the purlins 26, and the reinforcing members 27, the lower ends of the upper chords are preferably secured to the ends of the longitudinal members 20, on the lower chords, by suitable gusset plates 28-29. The purlins 26 extend transversely of the frame and are rigidly secured to the upper chord of each truss.

In Fig. 2 separated plates 30-31 project inwardly from the base of the lower chords 20 and 21. These plates are reinforced preferably by angles 32 and 33 which are positioned below the lower chords and riveted thereto. Positioned on the top of the plates and extending longitudinally thereof, there may be I-beam supporting members 34-35, which carry the tracks 36 and 37.

Traveling on the overhead tracks 36 and 37 is a supplemental frame which moves longitudinally of the main frame and therefore transversely of the freight platform. The supplemental frame comprises longitudinal members 40 and 41 with transverse end members 42 and 43. Transverse beams 44 and 45 extending parallel to the end beams 42 and 43 provide bearing surfaces for the wheels 46-47, which travel on the tracks 36-37.

To move the supplemental frame along the overhead trackway I provide pinions 48 and 49 intermediate gears on the wheels 46 and 47 and attached to the shaft 50. The shaft 50 may be rotated through the worm wheel 51, the sprocket chain 52 by the motor 53. Suitable control mechanism (not shown) is provided for operating the motor. A mechanical brake may be attached to the motor 50 to retard the motion of the supplemental frame when the motor is disconnected.

Intermediate the ends of the longitudinal members 40 and 41 of the supplemental frame, there may be additional transverse members 54 and 55. Extending between the members 54 and 55 and parallel to the longitudinal members 40 and 41 there may be supporting beams 56 and 57. These supporting beams serve to support a hoisting mechanism which will be hereinafter described.

Rotatably mounted on the longitudinal beams 40 and 41 are winding drums 58 and 59 which are rigidly secured to the shaft 60. The shaft 60 is rotated through the gear 61 and pinion 62 by the motor 63.

Extending outwardly from the rotating drums 58 and 59 are the cables 64 and 65, which pass over sheaves in the blocks 66 and 67, and which are rigidly secured to the transverse beams 54 and 55. The lower ends of the cable may be provided with any suitable load engaging means. I prefer to use loops 68 and 69 which are adapted to engage hooks 70 and 71 on the truck body 7. The cables are so arranged on the winding drums that a movement of the shaft 60 in one direction will wind in the cables, while a movement in the opposite direction will pay out the cables. Obviously when the cables are wound in the load depending therefrom will be raised, and when the cables are paid out the load will be lowered.

As hereinbefore stated, the body 7 is shown to be provided with engaging hooks 70 and 71. However, it is obvious that I may provide a cradle which depends from the lower ends of the cables, to engage suitable projections on the body 7. The hooks as shown and described have been presented merely for the purpose of illustration.

Suitable control cables 72 and 73 which depend from the supplemental frame are provided, so that an operator may control the movements of the frame and hoisting elements, from a position on the freight platform.

In Fig. 4, I have shown a partial layout of a freight platform provided with my travelling crane, having the street 80 on one side of the platform with the railroad tracks 81 on the other side. Assuming that a truck 74 having a loaded body 75 drives beside the platform from another terminal station, then the crane is moved longitudinally until the overhead trackway 36-37 is positioned directly over the removable body 75. In the meantime the supplemental frame is moved to the side of the platform on which the truck is standing, while at the same time, the cables are being lowered, so that when the main frame stops at the required position, the cables are ready to lift the body from the truck. The body is then lifted from the truck and moved inwardly and placed upon the platform as at 76. A loaded body 77 or an empty body 78 may then be picked up from the platform and loaded on the truck whereupon the truck will leave for a destination as directed by a freight dispatcher. The body which was removed from the truck may then be placed upon the freight car 79 without incurring any loss of time to the truck.

From the foregoing description, it will be seen that I have provided a crane adapted to travel over three parallel passageways, and to transport a removable automobile truck from one of the passageways to another; that the crane is adapted to lift one body over another and to deposit it when-

ever it is expedient to do so; and that I have provided a combination which greatly facilitates the handling of L. C. L. as well as car load shipments.

5 Having thus described my invention, I claim:

1. In combination, a platform intermediate a depressed automobile truck runway and a railroad track and raised above them, a 10 crane movable longitudinally of the platform and overhanging both the runway and the track, and hoisting mechanism movable on the crane and transversely of the platform, runway and track.

15 2. In a freight transfer system of the character described, the combination of an automobile truck runway, a railroad track on substantially the same level as the runway and a raised platform extending longitudinally between the runway and the track, a 20 gantry crane and rails therefor at each side of the platform, said crane extending transversely of and overhanging the runway, platform and track, a hoisting mechanism movable on the crane and adapted to raise and carry removable truck bodies.

3. A system for handling freight comprising loading the freight into removable interchangeable automobile bodies, transporting the bodies to a station platform, 30 depositing some of them on the platform raising others and transporting them over those on the platform, and then depositing the overhead bodies on transportation means without dispersing the contents.

35 4. A system for handling freight comprising storing it into containers in the form of interchangeable automobile bodies, transporting the bodies to a classification point, raising some of them and depositing them on a supporting surface, then raising other bodies and transporting them over those on the surface, by means of an overhead hoisting mechanism which is arranged 45 to raise bodies over twice the height of those on the supporting surface, and then depositing the overhead bodies on transportation means.

5. A system for handling freight comprising storing the freight in removable interchangeable automobile bodies, transporting the body to one edge of a station platform, removing it from the transportation means and then depositing it without dispersing 50 the contents interchangeably onto the platform or onto a transportation vehicle positioned at the opposite edge of the platform.

6. In combination, a raised platform a 55 depressed automobile runway extending along one side thereof, a railroad track on the other side thereof, a set of interchangeable automobile bodies each having load supporting members projecting above the top thereof, a main frame adapted to travel longitudinally 60 of the platform said frame having a boom

overhanging both the runway and the tracks, a supplemental frame carried by the main frame, and four hoisting cables depending from the supplemental frame, said cables being arranged to cooperate with the load 70 supporting members on the body.

7. In combination, a raised platform having a depressed automobile runway, a depressed railroad track extending along the opposite side of the platform, a main frame 75 movable longitudinally of the platform, a supplemental frame movable transversely thereof, a set of interchangeable automobile bodies on the platform, each of said bodies having pairs of hooks projecting above the top thereof, and hoisting mechanism mounted on the supplemental frame, said mechanism comprising four cables spaced to register with the body hooks.

8. In combination, a station platform 85 adapted to support removable automobile bodies, means adapted to engage and hoist a body, a trackway extending longitudinally of the platform, whereby the body may be moved longitudinally thereof, there being 90 provision for an automobile truck on one side of and below the platform, and provision for a railroad car on the other side of and below the platform, whereby a body may be lifted and transported from a truck to a 95 railroad car.

9. The combination with a station platform intermediate the street and railroad tracks, of a main frame movable longitudinally of the platform, overhead tracks carried by the said frame and extending transversely of the platform, a supplemental frame movable on said overhead tracks, said supplemental frame being substantially rectangular and having four sets of wheels, 105 gearing on two of the sets of wheels, a shaft connecting the gears, means for rotating the shaft, and a pair of hoisting drums mounted on the supplemental frame.

10. The combination with a platform 110 adapted to support removable automobile bodies, a depressed automobile truck runway on one side of the platform, railroad tracks on the opposite side of the platform, an overhead trackway extending beyond the sides 115 of the platform, a frame movable on the trackway, four sets of wheels rotatably mounted on the frame, gearing on some of said sets of wheels, means carried by the frame for operating said gearing, whereby 120 the frame is caused to move along the trackway therefor, a pair of winding drums on the frames, four cables leading from the drums, and means attached to the cables for raising a load.

11. The combination with a platform adapted to support removable truck bodies, of an overhead trackway extending beyond the sides of the platform, a frame movable on the trackway, four sets of wheels rotat- 130

ably mounted on the supplemental frame, gearing on two of the said sets of wheels, a shaft extending longitudinally of the supplemental frame and connecting the gears, means carried by the frame for operating the shaft whereby the frame is caused to move a pair of winding drums on the frame,

four cables leading from the drums, and means attached to the cables for raising a load.

10

In testimony whereof, I hereunto affix my signature.

BENJAMIN F. FITCH.
